MILK CARTON OR THE LIKE

Albert B. Mojonnier, Chicago, Ill., assignor to Albert
Mojonnier, Inc., Franklin Park, Ill., a corporation of Illinois

Filed Aug. 27, 1962, Ser. No. 71,470

Term of patent 14 years

(Cl. D58—17)

Fig. 1

Fig. 2

FIG. 3

FIG. 1 is a perspective view of a milk carton, showing my new design;

FIG. 2 is a top plan view of the same;

FIG. 3 is a front elevational view of the same; and

FIG. 4 is a side elevational view of the same.

The dominant features of my design reside in the proportions shown in full lines.

I claim:

The ornamental design for a milk carton or the like, substantially as shown and described.
